UNITED STATES PATENT OFFICE.

SIDNEY GEORGE BROWN, OF LONDON, ENGLAND.

TELEPHONE-RECEIVER.

1,096,676.

Specification of Letters Patent. Patented May 12, 1914.

Application filed March 27, 1911. Serial No. 617,228.

To all whom it may concern:

Be it known that I, SIDNEY GEORGE BROWN, a subject of the King of Great Britain, residing at 4 Great Winchester street, 5 in the city and county of London, England, have invented certain new and useful Improvements Relating to Telephone-receivers, of which the following is a specification.

This invention relates to the reproduction 10 of sound by electrical means and has particular reference to telephone receivers, the chief object being to enable a high efficiency of conversion of oscillations or variations of electric current into acoustic vibrations to 15 be obtained.

The usual telephone receiver consists of a polarized electromagnet through the coil of which the line currents pass, and a soft iron diaphragm gripped peripherally and 20 thereby held a short distance away from the electromagnet. Variations in the strength of the line current cause the diaphragm to vibrate, and, in so doing, to set the surrounding air into vibration. The 25 responsiveness of the diaphragm as usually employed and the transmission of its vibrations to the air are imperfect for several reasons. In the first place owing to the peripheral gripping of the diaphragm it 30 cannot vibrate uniformly at all points on its surface; also owing to the diaphragm serving to complete the magnetic circuit of the electromagnet, its thickness is considerable; and, owing to this thickness of the 35 diaphragm and to its being composed of iron, it is comparatively heavy with the result that its inertia makes it sluggish in action. Moreover in regard to the transmission of the vibrations through the air, sufficient 40 attention has not been paid to the volume of air set in motion and the variations of air pressure for producing the most effective transmission. The dimensions of the ear-drum and of the aural cavity may 45 be taken as invariable factors in such considerations. Now these factors being known, there are certain relations existing 50 between them and the size of the diaphragm, the nature of the air pressure variations, and the volume of air set in motion for the most effective reproduction of the sounds, and the transmission of them to the ear-drum.

The telephone receiver constructed in ac-

cordance with the present invention is de- 55 signed to eliminate the causes of inefficiency above referred to.

According to this invention the dia- 60 phragm of the receiver is made extremely light but is so shaped that notwithstanding its extreme lightness it is comparatively 65 rigid. I have found that a diaphragm of aluminium formed conically from a very thin disk of that metal and if necessary suitably stiffened by ribs, or corrugations, or otherwise, possesses the requisite properties to a satisfactory degree. The thin disk of aluminium may conveniently be spun into a conical shape with a flat center piece.

It is advantageous for the strength to be 70 greatest at the center and progressively less toward the edge, and by starting the spinning operation at the edge and working toward the center, this property of the spun disk will be naturally produced owing to 75 the graduated thickness of the disk. To increase this effect resort may be made to the known expedient of assembling several disks of different diameter into a pile. The thickness of such disks may be of the order of 2 $\frac{1}{2}$ 80 thousandths of an inch. Some idea as to the lightness of a diaphragm so formed may be gained from the fact that when it is allowed to drop to the ground it does not fall like a heavy mass of metal, but moves gently 85 through the air. The mere conical shape of the diaphragm will insure a considerable amount of rigidity but this may be increased by providing radial ribs or corrugations on it. This diaphragm is mounted upon a re- 90 silient member which responds to the variations of line current; the said resilient member may consist of a metal strip or reed containing within itself, by reason of a cut-away portion, its own control and that of 95 the diaphragm. The diaphragm is prefer- 100 ably attached at its center to a point on the metal strip or reed slightly eccentric with respect to the axis of the coil through which the line currents pass. The diaphragm is so arranged as to be free to move as a whole, that is to say all points on its surface vi- 105 brate equally, and to insure this action the periphery of the diaphragm is either quite free or is attached to the usual casing by a mere thin ring of flexible material. The inner face of the cover or ear-piece of the receiver is shaped to conform approximately

to the shape of the diaphragm, and is situated at a comparatively short distance from this diaphragm, thereby avoiding an undue amount of space between the diaphragm and 5 the cover or ear-piece.

In order that the invention may be clearly understood and readily carried into effect I will now describe the same more fully with reference to the accompanying drawings, in 10 which:—

Figure 1 is a plan with the cover removed, and Fig. 2 a sectional elevation, of one constructional form of my improved receiver. These drawings represent a full size receiver, and the more important dimensions 15 such as the diameter of the diaphragm, the extent of its eccentricity, and the volume and shape of the air space between the diaphragm and the ear-piece or cover, are what 20 I have found by experiment to give good results for hearing with the receiver close to the ear, by reason, no doubt, of the relation these dimensions bear to the diameter of the ear-drum and the volume of the aural 25 cavity. Where it is desired to make the sounds travel out into the room, a receiver of larger size is preferable. Fig. 3 is a detail view of a diaphragm built up of several diaphragms of different diameter.

30 A is the casing and B the ear-piece or cover of the receiver.

C represents the coil and D the core of a polarized electromagnet of which N and S are the north and south poles respectively.

35 E is a metal reed one end of which is held down upon a bridge piece E' on the casing E by two adjusting screws E²; the free end of this reed extends over the core D of the electro-magnet. A portion E³ of this reed is cut 40 away to increase its flexibility and decrease its weight. I have found that a suitable free period for the reed is from eight hundred to one thousand. The extent to which the reed E can approach the core D may be 45 regulated by packing some layers of paper between these parts or by arranging a set screw to make contact with the reed.

50 F is a light aluminium diaphragm of conical form. It is attached at its center to the reed E at a point eccentric with respect to the axis of the core D, the eccentricity being toward the fixed end of the reed. Although I have shown the best position for attaching the diaphragm in the particular receiver 55 illustrated, the best position on any reed can be found by experiment by means of a stethoscope and by exploring the reed with the aid of a movable diaphragm.

The diaphragm F is flexibly attached at 60 its periphery by a ring F' of tissue paper or other suitable material that will not exert appreciable restraint upon the diaphragm, to a removable flange on the casing A. This ring F' may be attached to the diaphragm 65 and to the aforesaid flange by adhesive.

It will be understood that owing to the extreme lightness of the diaphragm and to its freedom from peripheral constraint, it will be highly responsive to movements of the reed E and will vibrate as a whole. It will 70 also be observed that the function of the reed E is not to set the air in motion, but only to carry the diaphragm and control its movement. This reed contains, within itself, by reason of its cut away portion E', 75 the means of its own control and that of the diaphragm, and also serves to complete the magnetic circuit; the diaphragm forms no part of this circuit. The inner face of the cover or ear piece B conforms approximately to the shape of the diaphragm and its distance from the diaphragm is such as to give only the requisite air space between these two parts. The sectional area of the central hole or holes in the ear-piece is suitably proportioned to the aforesaid air space. 80

Although the invention has been described and illustrated with reference to a "watch" type of receiver, it is of course equally applicable to the long handle type of receiver. 90

What I claim and desire to secure by Letters Patent of the United States is:—

1. In a telephone receiver, a coil through which the line currents pass, a resilient metal reed responsive to variations of current in the coil, and having an intermediate cut-away portion to impart inherent flexibility, a light rigid peripherally unrestrained conical diaphragm carried by its center on said reed, and an ear piece situated over 95 the diaphragm.

2. In a telephone receiver, a polarized electromagnet, a coil through which the line currents pass, a resilient metal reed responsive to variations of current in the coil and 105 having an intermediate cut-away portion to impart inherent flexibility, a light peripherally unrestrained conical diaphragm carried by its center on said reed, and an ear piece situated over the diaphragm. 110

3. In a telephone receiver, a polarized electromagnet, a coil through which the line currents pass, a resilient member responsive to variations of current in the coil, a light peripherally unrestrained conical diaphragm 115 carried by its center on said member eccentrically with respect to the electromagnet, and an ear piece situated over the diaphragm.

4. In a telephone receiver, a polarized electromagnet, a coil through which the line currents pass, a resilient metal reed serving as electromagnet armature and having an intermediate cut-away portion to impart inherent flexibility, a peripherally unrestrained conical diaphragm carried by its center on the free end of the said armature, and an ear piece situated over the diaphragm. 125

5. In a telephone receiver, a coil through 130

- which the line currents pass, a resilient metal reed responsive to variations of current in the coil and having an intermediate cut-away portion to impart inherent flexibility, a light peripherally unrestrained conical diaphragm carried by its center on said reed, and an ear piece the inner face of which conforms approximately to the conical shape of the diaphragm.
6. In a telephone receiver, a casing, a polarized electromagnet attached to the back of the casing, a coil through which the line currents pass, a resilient metal reed responsive to variations of current in the coil and having an intermediate cut-away portion to impart inherent flexibility, a light conical diaphragm carried by its center on said reed with its apex pointing toward the back of the casing, and a cover or ear-piece with a conical inner face conforming approximately to that of the diaphragm.
7. In a telephone receiver, a diaphragm comprising a conically shaped sheet of metal thickest at the center and progressively thinner toward the periphery, and a resilient member for carrying said diaphragm by its center.
8. In a telephone receiver, a conically spun aluminium diaphragm thickest at the center and progressively thinner toward the periphery, and a resilient member for carrying said diaphragm by its center.
9. In a telephone receiver, a diaphragm comprising a sheet of metal having a flat centerpiece and a conical flange portion the thickness of which decreases progressively toward the periphery, and a resilient mem-
- ber for carrying said diaphragm by its center.
10. In a telephone receiver, an aluminium diaphragm comprising a flat centerpiece and a conically spun flange portion the thickness of which decreases progressively toward the periphery, and a resilient member supporting the diaphragm by its center.
11. In a telephone receiver, a casing, a coil through which the line currents pass, a resilient member responsive to variations of current in the coil, a light conical diaphragm carried by its center on said member, an ear piece situated over the diaphragm, and a flexible ring of material connecting the periphery of the diaphragm to the casing, said material being so thin and light as to exert no appreciable restraint upon the diaphragm.
12. In a telephone receiver, a casing, removable flange thereon, a polarized electromagnet, a coil through which the line currents pass, a resilient member responsive to variations of current in the coil, a light rigid diaphragm carried by said resilient member, and a thin flexible ring of material connecting the periphery of the diaphragm to the aforesaid removable flange, said material being so thin and light as to exert no appreciable constraint upon the diaphragm.
- In testimony whereof I affix my signature in presence of two witnesses.

SIDNEY GEORGE BROWN.
